TOY ANIMAL

John B. Hostetler, Sturgis, Mich.

Application May 8, 1957, Serial No. 46,070

Term of patent 14 years

(Cl. D34—15)

fig. 4

fig. 3

Figure 1 is a side elevational view of a toy animal, showing my new design, the opposite side having substantially the same appearance.

Figure 2 is a front elevational view.

Figure 3 is a rear elevational view; and

Figure 4 is a top plan view thereof.

The dominant features of the design reside in the portions shown in full lines.

I claim:
The ornamental design for a toy animal, as shown and described.
